(57) **CLAIM**

We claim the ornamental design for a stand for television receiver, as shown and described.

DESCRIPTION

FIG. 1 is a front perspective view of a stand for television receiver showing our new design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines shown in the drawings represent portions of the stand for television receiver that form no part of the claimed design. The dot-dash lines represent the boundary between the claimed and unclaimed portion line and form no part of the claimed design.
